UNITED STATES PATENT OFFICE.

NORMAN E. BROWN, OF ST. JOSEPH, MICHIGAN, ASSIGNOR OF THREE-FOURTHS TO MURWIN C. BARNES, EDWARD N. HATCH, JOHN EKLUND, AND JOHN LINDT, OF SAME PLACE.

OVERHEAD HOISTING AND CARRYING DEVICE.

SPECIFICATION forming part of Letters Patent No. 664,622, dated December 25, 1900.

Application filed September 14, 1900. Serial No. 30,018. (No model.)

To all whom it may concern:

Be it known that I, NORMAN E. BROWN, a citizen of the United States, and a resident of St. Joseph, in the county of Berrien and State 5 of Michigan, have invented a new and Improved Overhead Hoisting and Carrying Device, of which the following is a full, clear, and exact description.

The object of the invention is to provide a 10 new and improved overhead hoisting and carrying device which is simple and durable in construction and arranged to permit of quickly and safely raising a load, locking the same in position, and then transferring the 15 same overhead to a distant place.

The invention consists of novel features and parts and combinations of the same, as will be fully described hereinafter and then pointed out in the claims.

20 Reference is to be had to the accompanying drawings, forming a part of this specification, in which similar characters of reference indicate corresponding parts in all the views.

Figure 1 is a side elevation of the improvement with the driving-shaft in section and parts in dotted lines. Fig. 2 is a plan view of the same. Fig. 3 is a side elevation of the same with parts in a different position, and Fig. 4 is a transverse section of the improvement 30 on the line 4 4 in Fig. 1.

A carriage A, of any approved construction and provided with wheels B, is mounted to travel on an overhead track C, and in the frame of the carriage are mounted to turn 35 disks D, attached to a lever E, under the control of the operator, for simultaneously turning the disks D in their bearings. In the said disks D is journaled eccentrically a shaft F, carrying a friction-wheel G, and 40 on said shaft are also secured sprocket-wheels H, over which pass hoisting chains or ropes I, extending over guide-pulleys J J', a hook I' being on one end of the chain and a weight I² on the other end, so as to prevent slack in the chain during the time the 45 load is hoisted. The wheel G is adapted to be moved bodily in engagement with the peripheral surface of a driving-pulley K, secured on a driving-shaft L, journaled in suit-

able bearings attached to one end of the overhead track C. On the shaft L is secured a pulley L', connected by belt with other machinery, so that a rotary motion is given to the shaft L and the pulley K secured thereon.

When the several parts are in the position 50 shown in Figs. 1 and 2 and the carriage A is at one end of the track C and the operator has thrown the lever E into a vertical position, then the wheel G is in contact with the driving-pulley K, so that the wheel G is rotated, 55 and consequently the shaft F, with the wheels H, to impart a traveling motion to the hoisting-chains I, so that the load hung on the hook I' is hoisted. In order to lock the wheel G in frictional contact with the pulley K, 60 spools N are provided and mounted to rotate loosely on the shaft L, said spools being engaged by the inclined ends E' of arms E², projecting from the lever E, so that when the latter is thrown into a vertical position the said 65 ends E' engage the spools and hold the wheel G in frictional contact with the pulley K. By making the ends E' with inclines it is evident that the wheel can always be drawn in 70 firm contact with the pulley K, even if the 75 said wheel and pulley are reduced in size by wear. It is understood that when the ends E' of the arms E² move in engagement with the spools N then the carriage A is drawn to the left to bring the wheel G in firm frictional 80 contact with the pulley K. When the load has been hoisted, then the operator throws the lever E to the right to turn the disks D and move the wheel G out of frictional contact with the pulley K and to move it in 85 frictional engagement with a friction-block O, carried by the frame of the carriage A. When this takes place, the wheel G is locked against rotation, so that the hoisting-chain I, with its 90 load, remains stationary, and the carriage can now be moved along the track C to a distant place with the load and without danger of the load descending, owing to the locked position of the wheel G on the friction-block O.

When the carriage has been moved the desired distance and it is desired to lower the load, then the operator manipulates the lever E correspondingly by throwing the same grad-

ually to the left to allow the wheel G to rotate and the chain I to travel with the load descending and the friction-block O used as a brake to prevent a too-rapid descent of the load.

Having thus fully described my invention, I claim as new and desire to secure by Letters Patent—

1. An overhead hoisting and carrying device, comprising a carriage mounted to travel, a driven shaft having a driving-pulley, journaled in stationary bearings, a wheel on said carriage adapted to be geared with said pulley and controlling a hoisting chain or rope, a fixed friction-block carried by said carriage, and means for bodily moving said wheel in engagement with either the said driving-pulley or the said friction-block, said means being arranged to lock the wheel and pulley in position when thrown in gear, as set forth.
2. An overhead hoisting and carrying device, comprising a carriage mounted to travel, a driven shaft having a driving-pulley, journaled in stationary bearings, a wheel on said carriage adapted to be geared with said pulley and controlling a hoisting chain or rope, a fixed friction-block carried by said carriage, and means for bodily moving said wheel in engagement with either the said driving-pulley or the said friction-block, said means being arranged to lock the wheel and pulley in position when thrown in gear, said means being also arranged to compensate for any wear on the wheel and pulley to hold the latter in frictional contact, as set forth.
3. An overhead hoisting and carrying device, comprising a carriage mounted to travel, a driven shaft having a driving-pulley, journaled in stationary bearings, a wheel on said carriage adapted to be geared with said pulley and controlling a hoisting chain or rope, a fixed friction-block carried by said carriage, and means for bodily moving said wheel in engagement with either the said driving-pulley or the said friction-block, which means is arranged to lock the wheel and pulley in position when thrown in gear, said means comprising a disk in which the wheel is journaled eccentrically, the disk being mounted to turn in bearings on said carriage, a lever for turning the disk, an arm extending from the lever, and spools on the driven shaft and adapted to be engaged by said arm, as set forth.
4. An overhead hoisting and carrying device, comprising a carriage mounted to travel, a driven shaft having a driving-pulley, journaled in stationary bearings, a wheel on said carriage adapted to be geared with said pulley and controlling a hoisting chain or rope, a fixed friction-block carried by said carriage, means for bodily moving said wheel in engagement with either the said driving-pulley or the said friction-block, which means is arranged to lock the wheel and pulley in position when thrown in gear, said means comprising a disk in which the wheel is journaled eccentrically, the disk being mounted to turn in bearings on said carriage, a lever for turning the disk, an arm extending from the lever, and spools on the driven shaft and adapted to be engaged by said arm, the latter having an inclined edge to compensate for wear on the pulley and wheel, as set forth.
5. An overhead hoisting and carrying device, comprising an overhead track, a shaft journaled on said overhead track, and carrying a driving-pulley, a carriage mounted to travel on said overhead track, disks journaled on said carriage, a shaft mounted to turn eccentrically in said disks and carrying a wheel adapted to be thrown in gear with the said driving-pulley, a hoisting-chain controlled from said shaft, a lever on said disks, an arm on said lever, and spools on the track-shaft and engaged by said lever-arm, as set forth.
6. An overhead hoisting and carrying device, comprising a carriage, a fixed friction-block secured thereon, disks journaled in the frame of the carriage, a shaft journaled eccentrically in said disks, a wheel on said shaft and adapted to be thrown in frictional contact with said friction-block, a lever for turning the said disks, and a hoisting device controlled from said shaft, as set forth.

In testimony whereof I have signed my name to this specification in the presence of two subscribing witnesses.

NORMAN E. BROWN.
